(57) **CLAIM**

The ornamental design for a raiser used in stacked gigabyte interface converter guide rail assembly for removable optoelectronic modules, as shown and described.

DESCRIPTION

FIG. 1 is a perspective view of a raiser used in stacked gigabyte interface converter guide rail assembly for removable optoelectronic modules showing my new design;
FIG. 2 is a front view thereof;
FIG. 3 is a rear view thereof;
FIG. 4 is a left side elevational view thereof;
FIG. 5 is a right side elevational view thereof;
FIG. 6 is a top plan view thereof; and,
